TYPEWRITING MACHINE

Filed Dec. 24, 1927

UNITED STATES PATENT OFFICE

GEORGE G. GOING, OF MIDDLETOWN, CONNECTICUT, ASSIGNOR TO REMINGTON TYPE-WRITER COMPANY, OF ILION, NEW YORK, A CORPORATION OF NEW YORK

TYPEWRITING MACHINE

Application filed December 24, 1927. Serial No. 242,398.

My invention relates to type actuating mechanism adapted particularly to typewriting machines and other machines employing type bars for printing purposes. The chief object of the invention is to provide type bar actuating mechanism which is substantially noiseless in operation and is moreover readily adaptable to small typewriting machines or so-called portable typewriters.

10 To the above and other ends which will hereinafter appear, my invention consists in the features of construction, combinations of devices, and arrangements of parts herein-after described and particularly pointed out 15 in the claims.

15 The preferred form of the invention is shown in the accompanying drawings where-
in,

20 Fig. 1 is a front-to-rear fragmentary, vertical, sectional view taken about centrally of a typewriting machine embodying my invention.

25 Fig. 2 is a transverse, sectional view taken on a plane indicated by the section line 1—1 in Fig. 1, and

30 Figs. 3, 4 and 5 are fragmentary operating views.

35 As appears from Fig. 1, the machine embodying the present form of my invention 40 comprises a set of type bars 1 pivoted in an arc of a circle and adapted for front strike writing, said type bars having fixed pivots preferably in the form of an arcuate pivot wire 2 which is mounted on a type bar sup- 45 port or segment 3 of any suitable construc-
tion. The type bars are or may be disposed in guide slots 4 cut radially in the lower end portion of the segment, which segment inclines upward and rearward towards the 50 platen 5. Said platen is diagrammatically illustrated and may be mounted on a suitable carriage adapted to travel back and forth transversely of the machine. Each type bar carries a type block 6 which is preferably pro- 55 vided with two types, a lower case type 7 and an upper case type 8. Normally, the lower case types are effective to print, but the upper case types may be rendered operative at will by relatively shifting the platen and 60 type bars in any known manner. The free

end portions of the type bars are supported on a suitable rest 9 and are inclined in a direction forward and upward from their pivots 2, being so related to the printing point on the upper front quarter of the platen that when actuated to print, the type bars are swung upward and rearward and then downward to coact with the platen. As is well understood, the type bars at and near the middle of the system are substantially 65 straight throughout their lengths, while the outer type bars are bent near their type ends to varying extents in order to bring their types in proper relationship with the printing point on the platen.

65 The actuating devices for the type bars comprise a set of keys and suitable operating connections between the keys and the type bars. As shown herein, such connections comprise links 10, one for each type bar, each link being connected at its forward end at 11 to its type bar, the rear end of the link being connected at 12 to a sublever 13 which is pivotally connected at 14 to the associate key lever 15. The under portion of 70 each sublever is provided with a curved bearing face or nose 16 which rests on and co- 75 operates with a transversely extending support or bar 17 arranged below the sublevers and key levers and suitably mounted on the 75 frame of the machine. The bearing bar 17 is provided with an upward angular extension 17^a which is formed with vertically disposed guide slots 18 adapted to accommodate and 80 guide the key levers 15 and the sublevers 13, 85 preferably in the manner more fully disclosed in my co-pending application, Sr. No. 232,582 filed November 11, 1927 (now Patent No. 1,767,875, June 24, 1930). During print- 90 ing operations the sublevers are adapted 95 through their bearing faces 16 to ride or slide on and over the horizontal face of the bar 17, the construction affording a lost motion or yielding connection between each key and key lever and the type bar operatively connected thereto. The key levers 15 are arranged in substantial parallelism extending fore and aft of the machine and at their rear ends are provided with round holes 19 which receive a fulcrum rod 20 having flattened op- 100

posite sides as shown to enable it when half turned relatively to the key levers to pass through cut outs or slots 21 in the key levers, whereby a detachable mounting between the key levers and the fulcrum wire is effected. Said fulcrum rod is suitably supported at its ends on ears 22 depending from a frame bar 23. The key levers 15 extend forward and may be guided near their front ends in a stationary slotted plate or comb 24, the forward end portions of the key levers terminating in upward extensions or stems 15^a to the tops of which are secured key caps or keys 25. The key levers are of varying lengths and their stems of varying heights, enabling the keys 25 to be disposed in banks or rows at different elevations, as is well understood, there being four banks in the present instance constituting the keyboard of the machine. To promote compactness the stem portions 15^a of the rearmost bank are curved or off-set rearward, as indicated at 15^b, thereby enabling the keyboard and the type bars to be brought closer together. The long stem portions of the rear bank may be provided with a guide comb 26 secured to or bent forward horizontally from the top of the guide plate 24. Said guide plate may be provided with seats or supports 27 and 28, which accommodate stop devices 29 and 30 extending transversely of the set of key levers and disposed respectively above and below the same. Said stop devices may be of any suitable construction and composition, and are so disposed that the stop 29 is engaged by the forward end portions of the key levers when they are in normal position while the stop 30 is adapted to arrest the key levers at the end of their downward movement. Preferably, the movement or stroke of the key levers is restricted so that they are arrested by the stop 30 before their type bars are brought into contact with the platen. It is to be understood however that a stop to limit the downward movement of the key levers is not essential to the noiseless operation of the type bars according to this invention.

When a key 25 is depressed its associate key lever 15 will be actuated, thereby operating the associate sublever 13, which pivoting variably during its movement on the support 17 will press or push the associate link 10 forward. Said link in turn will actuate the connected type bar to swing it about its pivot from normal position towards the platen. Restoring springs 31 are provided one for each type action, the set of springs 31 being horizontally disposed above the key levers at their rear, each spring being hooked at its forward end through a hole 32 in the associate sublever 13. The rear ends of the springs are anchored to an angular plate 33 fixed to the frame plate 23. In order to prevent the adjacent sublevers from interfering

with the proper operation of these springs their forward end portions are preferably formed with long loops 31^a.

Preferably each type bar is provided with a contact face 34 which is adapted near the end of the stroke to contact with and operate a spring-pressed universal bar 35 connected to and effective to actuate the escapement mechanism. Said mechanism and its connections (not shown herein) may be of any suitable construction. The universal bar proper is arcuate in shape and is disposed in a corresponding slot 36 cut or otherwise formed in the rear lower portion of the segment 3.

It will be apparent that the type bars are arranged in the arc of a circle and in an inclined position, while the key levers are horizontally disposed and in parallelism, the set of key levers as a whole being of greater width than the set of type bars. Also, the type bars swing in radial planes, whereas the key levers swing in parallel vertical planes. However, the type bars are actuated by impulses received substantially in their planes of movement by reason of the connections with the key levers afforded by the set of sublevers 13. The rear arms of said sublevers vary in length, increasing progressively from the middle to the sides of the system, and most of them are bent or twisted back of their fulcrums so as to bring the upper end portions of said sublevers substantially into the planes of the type bars with which they are connected. To compensate for the varying lengths of the rear arms of the sublevers, their forwardly extending horizontally disposed arms also vary in length so that the extents of movement communicated to the type bars by their keys are substantially equal.

In the present instance, the means for controlling and governing the type bars so as to minimize the noise of printing operations and substantially silence the printing contacts of the types comprise for each type bar a controlling or governing device which is in the form of a pivoted member 37. The set of members 37 is pivotally supported on a common fulcrum wire 38 suitably secured to a plate or support 39 that is disposed in substantial parallelism with the type bar segment 3 and is arranged forward of and below said segment, being provided with ears or tabs 40 whereby it may be secured to stationary side parts of the machine. The support 39 is preferably of sheet metal and may correspond substantially in construction with the support or the governing device disclosed in my prior application aforesaid. Said support 39 is provided with an upwardly extending part 41 which is formed with a series of radially cut kerfs or guide slots 42 that receive and guide the members 37, the fulcrum 38 whereof is suitably secured to the top face of the part 41.

The members 37 are normally disconnected from the type bars and are adapted to be picked up by the type bars as they approach the printing point and then to begin to control the movements and operations of the type bars. To this end each governing device is formed with a slot 43 extending downward and rearward from near the pivot 38 and terminating in a flaring mouth or entrance way. This provides the member 37 with two arms, which for descriptive purposes may be numbered 44 and 45. The members 37 are preferably made each of a single piece of sheet metal and in order to give them sufficient weight the arms may have soldered to them suitably shaped pieces of lead so that an edge-view of one of the members 37 will show a form somewhat like Fig. 2. Care must be taken however to limit the width of the weighted arms so that adjoining members will not interfere with each other or with other parts. The members 37 have fixed pivots or axes around which they rotate in fixed circular paths. Normally the members may rest on the rear edge portion of the support 39, which may be lined with felt 39^a or some other sound deadening material, the inner rounded corner of this material serving as a stop which normally supports the members 37 and limits their pivotal movements in one direction. To limit pivotal movements, or swings of the members in the opposite direction and prevent them from being accidentally dislocated, each member is provided with a stop face 46 which is adapted to contact with the front face of the rib or flange 41 below the slots 42, the contact faces 41^a serving as stops, which in cooperation with the stops 46, limit swinging movements of the members 37 away from normal position.

It will be understood from the dotted-line showing of the member 37 in Fig. 1, that each stop 46 does not coact with its companion stop 41^a to limit the printing movement of the type bar in the operation of the machine, but such stops are intended to function only to prevent an undue displacement of the members 37 when the machine is being moved or transported. For example, in the event that the machine is turned upside down in transporting it, the stops in question will prevent the members 37 from swinging to a position from which they cannot drop back to normal position in cooperative relation with the pins 47 on the type bars when the machine is again turned over in a position for use. Obviously, if the members 37 could be accidentally displaced and maintained in the displaced position in the manner indicated, then said members would be ineffective on the type bars when the machine is actuated. However, by use of the stops 46 and 41^a the members 37, even in the event that the machine is turned upside down, can never be displaced to a position from which they cannot drop down into cooperative relation with the pins 47 when the machine is turned over in position for use.

In order to effect connection and cooperation between the type bars 1 and the controlling or silencing devices 37 each type bar is provided with an extension or tail portion 1^a which receives a laterally extending device or pin 47. It will be understood that the underlying members 37 are arranged in relation to their associate type bars in such a way that when one of the type bars is actuated the pin 47 carried thereby will enter the mouth of the slot 43 in the associate member 37 and will coact with the slot in such a way as to cause an effective cooperation between the type bar and the controlling member. During the first part of its printing movement the type bar will be entirely free from and independent of the controlling member, which will remain undisturbed in normal position. As the type bar in the course of its movement approaches the dotted line position indicated at *x*, the pin 47 will begin entering the slot 43 and will engage with the under side of the arm 44, as shown in Fig. 3. The under side of course forms the upper wall or face of the slot 43, and is so shaped or curved that it provides a cam with which the pin 47 contacts to pick up and start pivotal movement of the member 37 without undue shock or jar. The coaction of the parts, as illustrated at Fig. 3, begins preferably just prior to the arrest of the actuated key lever by the stop 30, so that movement of the controlling member 37 begins before the arrest of said key lever and before positive movement of the type bar by its key 25 ceases. The momentum of the type bar is sufficient to carry it on towards the platen and communicate movement to the controlling member 37, which will begin to turn on its axis so as to substantially slow down and control the movement of the type bar in the vicinity of the platen, this point being designated by the dotted line position *y* of the type bar, the corresponding relation of the pin 47 and the member 37 being shown in Fig. 4. From this point on until the type bar contactively engages with the platen, as illustrated by the dotted line position *z*, the type bar will be rapidly slowed down by the controlling member so that it will be moving at a minimum rate of speed when it contacts with the platen, whereby the noise is minimized, and the operation is rendered substantially silent. The position of the parts at the time of contact is illustrated at Fig. 5 and also by the dotted lines in Fig. 1.

From an inspection of this figure, it will be apparent that the chief reason for the slowing down of the type bar is the approach of the pin 47 close to the fixed axis of rotation 38. Since the pin is closely confined at this

time near the closed end of and between the contiguous walls of the slot 43 the type bar can move no faster than the controlling member 37, and as the construction is such 5 that at this time the pin 47 is very close to the center of rotation the movement will be comparatively slight. It has been found in practice that the closer the pin 47 can be brought to the axis of rotation the less will 10 be the striking noise of the type bar, and experience has shown that a difference in distance of a mere one-eighth of an inch will have a marked effect on the noise. It is therefore desirable that the pin at this stage 15 be brought as close to the axis 38 as the exigencies of a practical construction will permit. As explained at length in my prior application aforesaid the effect alone of slowing down the type bar so that it is moving 20 at its lowest speed at the moment of contact would be to afford such a faint imprint of the type through the usual ribbon as to be useless from a practical standpoint. However, the controlling device 37 after contact 25 will further act on the type bar to press the operated type with considerable force towards or against the platen with the result that a sufficient pressure is generated to obtain a clear and correct imprint. It will be 30 apparent that just prior to the arrest of the type bar and subsequent thereto it will be governed and controlled to a less or greater extent by the device 37, so that the movement of the type bar at the moment of contact 35 with the platen will have substantially ceased, although after such contact the printing pressure of the type will occur. The movement of the type bar subsequent to the arrest of the key lever will be uninterrupted, 40 due to the yielding connection comprising the sublever 13 between the type bar and its key lever.

After operation the parts will be restored to normal position by the restoring spring 45 mechanism and the force of gravity.

It will be seen that the member 37 is in effect a controlling or governing device for the type bar or carrier which substantially silences its operation, this result being due 50 to the dual function of the member 37 which controls the type bar in such a way that movement is practically eliminated at the instant of contact with the platen and subsequently to such contact an effective but silent 55 pressure is exerted to cause a clear and legible imprint of the type carried by the type bar.

It will be apparent that the present invention embodies certain of the principles involved and disclosed in my prior application 60 aforesaid whereby a controller or silencer is employed in combination with a type bar to substantially eliminate movement at the moment of contact and thereafter to communicate 65 printing pressure.

Various changes may be made without departing from my invention.

What I claim as new and desire to secure by Letters Patent, is:—

1. In type actuating mechanism, the combination of a type bar, a device fixed to said type bar, key operated means for actuating the type bar, and means normally disconnected from the type bar and rendered effective by said device for controlling said type bar near the end of the printing stroke, said last recited means comprising a member having a fixed pivot and formed with an open-mouth slot for receiving said device. 70

2. In type actuating mechanism, the combination of a pivoted type bar provided with a tail portion, a pin projecting laterally from said tail portion, a printing key, connections between said key and said type bar, and a controlling device having a fixed pivot, said controlling device being weighted and being formed with a slot engageable by said pin as said type bar approaches the printing point. 80

3. In type actuating mechanism, the combination of a pivoted type bar provided with a tail portion, a pin projecting laterally from said tail portion, a key, connections between said key and said type bar, a weighted controlling device having a fixed pivot and being formed with a slot engageable by said pin as said type bar approaches the printing point, and stops for limiting pivotal movements of said device in both directions. 90

4. In a typewriting machine, the combination of a platen, a plurality of type bars arranged in an arc of a circle, a plurality of parallel key levers, sublevers pivoted one to each key lever and having an arm connected to the associated type bar, actuating pins fixed to the tail portions of the type bar, and weighted controlling devices one for each type bar, said devices having fixed pivots and being formed with open slots for cooperation with said pins. 100

5. The combination of a plurality of type bars, actuating means for each of said type bars, a stop coacting with each of said actuating means before the companion type bar reaches the printing point, and means comprising a plurality of disconnected single pivoted members one for each type bar and normally disconnected from and movable relatively thereto for causing the associated type bar to print after said stop becomes effective. 110

6. The combination of a plurality of swinging type bars, a type secured to each type bar, key operated means associated with each type bar for actuating it, a stop coacting with each actuating means before the companion type bar reaches the printing point, means for affording movement of the actuated type bar to print after said stop becomes effective, and means for forcing the type bars to the printing position to effect 125 130

substantially a noiseless pressure imprint comprising a plurality of controlling members one for each type bar and free from control of the associated type bar in the early 5 position of its movement to the printing position but operative thereby for controlling the movement of its type bar after the associated key operated means has been arrested to decrease the speed of the actuated type 10 bar and cause it to exert an effective pressure imprint at the printing point.

7. The combination of a platen, a plurality of type bars pivoted in front of and below the platen and normally inclined away 15 therefrom, a type fixed to each of said type bars, means for actuating said type bars towards the platen to a limited extent about the type bar pivot as a fixed center, and means forcing the type bars to the printing position to effect substantially a noiseless 20 pressure imprint comprising a plurality of controlling members one for each type bar, each controlling member being normally wholly disconnected from the companion type bar but operative thereon to force it to cooperate with the face of the platen to effect 25 a pressure imprint.

8. The combination of a platen, a plurality of type bars pivoted in front of and below the platen and normally inclined away therefrom, a type fixed to each of said type bars, means for actuating said type bars towards the platen to a limited extent about the type bar pivot as a fixed center, and means for forcing the type bars to the printing position 30 to effect substantially a noiseless pressure imprint comprising a plurality of controlling members one for each type bar, each controlling member being normally wholly disconnected from the companion type bar but operative thereon to force it to cooperate with the face of the platen to effect a pressure 35 printing operation, each of said controlling members being actuated initially by the companion type bar itself.

9. The combination of a platen, a plurality of type bars each having a fixed pivot, means for actuating each of said type bars comprising a key lever and a lost-motion connection 40 between said key lever and the associated type bar, a stop for said means, and means operating after said stop becomes effective for reducing the speed of the actuated type bar and communicating printing pressure 45 thereto, said last recited means comprising a single separate controlling member for each type bar, each controlling member being normally free from control of its type bar and having a fixed pivot about which it is rotatable in a fixed circular path.

10. The combination of a plurality of type bars each having a fixed pivot, means comprising a key for actuating the type bar from 50 normal position, and other means comprising 55 a plurality of controlling members one for

each type bar, each controlling member having a fixed pivot on which it turns in a fixed circular path and normally disconnected from but effective to actuate the associated type bar near the end of the printing stroke. 70

11. The combination of a plurality of type bars each having a fixed pivot, means comprising keys for actuating the type bars from normal position, other means effective to actuate the type bar near the end of the printing stroke, said other means comprising a separate controlling member for each type bar mounted to turn on a fixed pivot, and stops cooperating directly with said controlling members for limiting the pivotal movements thereof in both directions. 75 80

12. The combination of a plurality of type bars each having a fixed pivot, means comprising keys for actuating the type bars from normal position, and other means comprising a plurality of controlling members one for each type bar and each having a fixed pivot and normally disconnected from the associated type bar for controlling it near the 85 end of the printing stroke. 90

13. The combination of a plurality of type bars, key operated means for controlling each type bar during the initial stages of its movement, and other means comprising a plurality of controlling members one for each 95 type bar, each controlling member having a fixed pivot and free from control of its associated type bar during the first portion of the printing stroke of the latter but cooperative therewith for controlling said type bar 100 during its last stages of movement and when cooperating with the platen.

14. The combination of a plurality of type bars, key operated means for controlling each type bar during the initial stages of its movement, and other means for controlling each of said type bars during its final stages of movement, said other means comprising a plurality of weighted controlling members each having a fixed pivot, one of said members associated with each type bar and out of control thereof during the initial stages of movement of its type bar but actuated by the type bar itself during the later stages of movement of the type bar and effective to move 110 the type bar in the final stages of its printing movement. 115

15. The combination of a plurality of type bars, a device fixed to each of said type bars, key operated means for actuating the type 120 bars, and a plurality of weighted controlling members one for each type bar, each of said members being normally disconnected from the associated type bar and rendered effective by said device thereon for controlling 125 the type bar near the end of the printing stroke and exerting its force on the type bar to complete its printing movement.

16. In a type action, the combination of a plurality of swinging type bars, and means 130

for controlling said type bars comprising a plurality of individually operable controlling members, one for each type bar, each controlling member being arranged in the path of the associated type bar to be picked up and actuated thereby after the type bar has first moved independently of its member during the printing stroke, the momentum of each controlling member thus actuated being exerted on its type bar to effect an imprint, whereby noise is eliminated and the initial printing stroke of each type bar is unhampered by said controlling means.

17. In a typewriting machine, the combination of a plurality of type bars, and a plurality of weighted type bar controlling members one for each of said type bars, each of said controlling members constituting a momentum accumulator out of control of its type bar during the first portion of the printing movement of the type bar but in cooperative relation therewith to be actuated thereby and then to actuate the type bar during the last portion of its printing movement by the momentum of the controlling member.

18. In a typewriting machine, the combination of a pivoted type carrier, key actuated means for effecting an initial printing movement of said type carrier, and a pivoted controlling member normally disconnected from said type carrier but arranged in the path thereof to be picked up and actuated by the type carrier as the latter approaches the printing position, the last stages of the printing movement of the type carrier being effected by the momentum of the controlling member, the type carrier and the controlling member turning in opposite directions one from the other on their pivotal axes.

19. In a typewriting machine, the combination of a pivoted type carrier, key actuated means for effecting an initial printing movement of said type carrier, and a pivoted controlling member normally disconnected from said type carrier but arranged in the path thereof to be picked up and actuated by said type carrier as the latter approaches printing position, the last stages of the printing movement of the type carrier being effected by the momentum of the controlling member, the portion of the type carrier which coacts with the controlling member advancing towards the pivotal axis of the latter as the type carrier approaches the printing point.

20. In a typewriting machine, the combination of a pivoted type carrier, key actuated means for effecting an initial printing movement of said type carrier, and a pivoted controlling member normally disconnected from said type carrier but arranged in the path thereof to be picked up and actuated by the type carrier as the latter approaches the printing position, the last stages of the printing movement of the type carrier being ef-

fected by the momentum of the controlling member, the type carrier and controlling member turning in opposite directions one from the other on their pivotal axes and the portion of the type carrier which coacts with the controlling member advancing towards the pivotal axis of the latter as the type carrier approaches the printing point, whereby at the last stages of the printing stroke a gradual slowing up of the type bar is effected and a gradual increasing speed of the controlling member is produced and the momentum thereof is transmitted to the type carrier to complete its printing movement with a pressure imprint.

21. In a typewriting machine, the combination of a pivoted type carrier, key actuated means for effecting an initial printing movement of the type carrier, and a pivoted controlling member normally disconnected from said type carrier but arranged in the path thereof to be picked up and actuated by the type carrier and to effect an interlocking connection therewith as the latter approaches the printing position, the last stages of the printing movement of the type carrier being effected by the momentum of the controlling member, the type carrier and controlling member turning in opposite directions one from the other on their pivotal axes and the return of the controlling member aiding in effecting a rapid return movement of the type carrier.

22. In a typewriting machine, the combination of a pivoted type carrier, key actuated means for effecting an initial printing movement of said type carrier, and a pivoted controlling member normally disconnected from said type carrier but arranged in the path thereof to be picked up and actuated by the type carrier and to effect an interlocking connection therewith as the latter approaches the printing position, the last stages of the printing movement of the type carrier being effected by the momentum of the controlling member, the portion of the type carrier which coacts with the controlling member advancing towards the pivotal axis of the latter as the type carrier approaches the printing point, whereby at the last stages of the printing stroke a gradual slowing up of the type bar is effected and a gradual increasing speed of the controlling member is produced and the momentum thereof is transmitted to the type carrier to complete its printing movement with a pressure imprint.

23. In a typewriting machine, the combination of a plurality of type bars, a plurality of movable controlling members one for each type bar for effecting substantially a noiseless pressure imprint from its associated type bar, each controlling member in the normal disposition of the parts being disconnected from but arranged in cooperative

relation with its associated type bar to be actuated thereby, and stops for each controlling member to prevent it from being accidentally displaced to a position from which it cannot return to cooperative relation with the associated type bar, said stops being ineffective one on the other in the operation of the machine.

24. The combination of a plurality of swinging type bars, and independently operable individual actuating means associated with each type bar, each actuating means comprising a key for actuating the type bar, and separate movably mounted actuating and controlling means for causing the associated type bar to be applied with a substantially noiseless pressure imprint, each of said actuating and controlling means being normally disconnected from and actuated by the associated type bar and effective to control it near the end of the printing stroke.

25. The combination of a plurality of swinging type bars, actuating means for operating the type bars, and independently operable individual controlling and actuating means associated with each type bar for actuating and causing it to be applied with a substantially noiseless pressure imprint, each controlling means being normally disconnected from its associated type bar but operative to control the movement thereof as the latter nears the printing point to reduce the speed thereof and react thereon to cause it to exert an effective pressure imprint.

26. The combination of a plurality of pivotally mounted type bars, key operated means for actuating the type bars, and additional means for forcing the type bars to the printing position to effect substantially a noiseless pressure imprint comprising a plurality of controlling elements one for each type bar, each of said controlling elements being free from control of its type bar during the initial portion of the printing movement thereof but operative by its type bar for controlling the movement of the bar and operating thereon to apply a pressure imprint.

27. In a typewriting machine, the combination of a plurality of type bars, means for effecting a substantially noiseless pressure imprint of said type bars comprising a plurality of movable type bar controlling members which operate as momentum accumulators one for each of said type bars, each of said controlling members being out of control of its type bar during the first portion of the printing movement of the type bar but in cooperative relation with its type bar to be actuated thereby at the last portion of the printing movement of the type bar, and stops for preventing the movement of each controlling member to a position from which

it cannot return to cooperative relationship with its type bar when the machine is in position for use.

Signed at Middletown, in the county of Middlesex, and State of Connecticut, this 70

20th day of December, A. D. 1927.

GEORGE G. GOING.
